UNITED STATES PATENT OFFICE.

LUCIEN J. BARIBAULT, OF WEST HAVEN, CONNECTICUT, ASSIGNOR OF ONE-HALF TO
LEWIS M. RYMAN, OF NEW HAVEN, CONNECTICUT.

DESIGN FOR A VELOCIPED-FRAME.

57,807.

Specification for Design.

Patented May 10, 1921.

Application filed April 29, 1920. Serial No. 377,721. Term of patent 7 years.

To all whom it may concern:

Be it known that I, LUCIEN J. BARIBAULT, a citizen of the United States, residing at West Haven, in the county of New Haven and State of Connecticut, have invented a new, original, and ornamental Design for a Velocipede-Frame, of which the following is a specification, reference being had to the accompanying drawing, forming part thereof.

Figure 1 is a side elevational view of a tricycle showing my new design, and

Fig. 2 is a top plan view.

I claim:

The ornamental design for a velocipede frame as shown.

LUCIEN J. BARIBAULT.
